MATCH HOLDER

Kenneth P. Nash, 14719 Avis Ave.,
Lawndale, Calif. 90260

Filed Apr. 21, 1971, Ser. No. 136,283

Term of patent 7 years

Int. Cl. D27—99

U.S. Cl. D48—28

FIG. 1.

FIG. 2.

FIG. 3.

FIG. 4.

FIG. 1 is a perspective view of a match holder showing my new design;

FIG. 2 is a side elevational view thereof;

FIG. 3 is a top plan view thereof; and

FIG. 4 is an end elevational view thereof.

The matches are shown in broken lines in FIG. 1 for illustrative purposes only.

I claim:

The ornamental design for a match holder, substantially as shown and described.
